CLAIM

The ornamental design for a charging dock, as shown and described.

DESCRIPTION

FIG. 1 is a top, front perspective view of a charging dock embodying our new design;

FIG. 2 a front view thereof;

FIG. 3 a rear view thereof;

FIG. 4 a top view thereof;

FIG. 5 a bottom view thereof;

FIG. 6 a side view thereof as seen from the left-hand side of FIG. 2;

FIG. 7 a side view thereof as seen from the right-hand side of FIG. 2;

FIG. 8 is a bottom, front perspective view thereof;

FIG. 9 is a top, front perspective view thereof with environment aligned for docking; and,

FIG. 10 is a top, front perspective view thereof with environment docked.

In the drawings, the broken lines are for the purpose of illustrating portions of the charging dock that form no part of the claimed design. In FIGS. 9 and 10, the broken lines are also for the purpose of illustrating environment that form no part of the claimed design.

1 Claim, 10 Drawing Sheets
